Primary Examiner — Mimosa De(74) *Attorney, Agent, or Firm* — Michael Best & Friedrich LLP(57) **CLAIM**

We claim the ornamental design for a chair component, as shown and described.

DESCRIPTION

The patent or application file contains at least one drawing executed in color. Copies of this patent or patent application publication with color drawing(s) will be provided by the Office upon request and payment of the necessary fee.

FIG. 1 is a plan view of a first embodiment of a backrest.
FIG. 2 is a plan view of a first embodiment of a seat.

FIG. 3 is a plan view of a second embodiment of the backrest.
FIG. 4 is a plan view of a second embodiment of the seat.
FIG. 5 is a plan view of a third embodiment of the backrest; and,

FIG. 6 is a plan view of a third embodiment of the seat.

1 Claim, 3 Drawing Sheets
(3 of 3 Drawing Sheet(s) Filed in Color)
